ERIC MOARD, OF EAST HAMPTON, CONNECTICUT, ASSIGNOR TO BEVIN BROTHERS MANUFACTURING COMPANY, OF EAST HAMPTON, CONNECTICUT, A CORPORATION OF CONNECTICUT.

SIGNAL-HORN.

1,294,936.

Specification of Letters Patent. Patented Feb. 18, 1919.

Application filed October 1, 1915. Serial No. 53,506.

To all whom it may concern:

Be it known that I, ERIC MOARD, a citizen of the United States, and a resident of East Hampton, in the county of Middlesex and State of Connecticut, have invented certain new and useful Improvements in Signal-Horns, of which the following is a full, clear, and exact description, whereby any one skilled in the art may make and use the same.

The invention relates, as indicated by its name, to signal horns or signal devices wherein a diaphragm is mechanically agitated to produce a vibrant sound.

It relates more particularly to devices which are commonly employed for motor vehicles, launches, boats or fog-signals or in fact, wherever a signal or alarm device is desirable. It belongs to a well-known type of such devices wherein a diaphragm is employed for vibrating the air.

More specifically, it pertains to the class of devices in which a diaphragm is vibrated at high velocity and with an amplitude which is sufficient to produce sounds of great intensity.

The essence of the invention as hereinafter defined, pertains to the mechanism and the adjustments of the mechanism through which a diaphragm may be actuated to the varying degrees of intensity by the operator.

The invention as hereinafter described, embodies a mechanism so actuated that a greater or less amount of force may be applied by the operator, and it is within the power of the operator in manipulating the device to secure the greatest intensity of applied force to the vibratory diaphragm almost instantly, or he may gradually apply the force.

By the manipulation of the mechanism, any desired tone may be secured.

It will be apparent that the mechanism provides a means whereby an extremely sharp high-pitched note may be sounded during a full period of operation, or the note may be varied to a gradually ascending and descending pitch. In fact, great latitude of operation is possible and the note of the horn may be raised and lowered at will, or may be maintained as desired by a proper manipulation of the actuating mechanism.

The device as above described, differs by comparison with the so-called electric motor horns or power driven signaling devices

wherein the full intensity of vibration of a diaphragm cannot be instantly secured. This is due primarily to inertia of the parts and to the fact that a motor or similar device of comparatively small size and power must be brought up to its full torque and speed before such a condition can be approximated. In such motor driven signals, the size of the motor and the consequent possible application of power is, of necessity, very limited. In the arrangement herein described, there is practically no limit to the power as it is possible for the operator to apply an extremely heavy pull upon the mechanism, developing an unusual power almost instantly and transmitting an operating force which is incomparably greater than that of the limited sized motor ordinarily employed.

The object of the invention is to provide a simple compact device, in which the manipulation of the vibratory mechanism or diaphragm will be under manual control and subject to variation at the will of the operator.

A further object is to provide a multiplying mechanism which will induce high rates of speed upon the agitating shaft, subject to the control and the modification of the operator at will.

It is a further object of the invention to provide for positive adjustment of the various parts from the exterior of the casing. The adjustments are such, that an initial coarse adjustment may be secured and subsequently a finer adjustment of the actuating mechanism may be effected for tuning the horn.

Referring to the drawings:

Figure 1 is a sectional view with parts broken away to illustrate the construction.

Fig. 2 is a front face view of the main casing and mechanism with the diaphragm removed.

Fig. 3 is a detail face view of the rear plate bearing the mechanism.

Fig. 4 is a detail sectional view through the main driving shaft and appurtenant parts.

Fig. 5 is a detail face view of the gears and rear plate, the front plate being removed.

Fig. 6 is an interior face view of the spring barrel.

Fig. 7 is a fragmentary view of the dia-

phragm showing the position and arrangement of the anvil or hammer which is engaged by the actuating cam.

Fig. 8 is a sectional view through the cam 5 spindle and appurtenant parts showing the adjustments thereof.

The mechanism is entirely inclosed in a suitable casing and is made adjustable from the exterior of said casing.

10 In the drawings, the numeral 1, denotes a horn or resonator which is secured to a cup-shaped flange 2, between which and a flange 3, of a cylindrical casing 4, is clamped a diaphragm 5.

15 The diaphragm 5, bears a hammer or anvil 6, which as illustrated in Fig. 7, consists of a plate portion 7, with the struck up anvil portion 6. The plate 7, is secured to the diaphragm by rivets 8. This anvil 6, is of 20 course of hardened material and is struck by an actuator or cam 9.

A suitable bracket is provided for supporting the horn structure in any desired position. The bracket is not illustrated in 25 the drawings.

It is to be understood that the form of the casing, bracket and horn or resonator may be varied to suit various tastes in designs.

As illustrated herein, the main casing is 30 of cylindrical form, and the entire mechanism, with exception of the pull cord and appurtenant parts, is arranged within this casing and may be adjusted bodily therein, in order to bring the cam 9, into a more or 35 less close juxtaposition with reference to the anvil 6, of the diaphragm.

The entire mechanism is supported in a frame-work consisting of a pair of plates 10, 11. These plates are spaced apart by 40 tubular members 12, through which pass bars or rivets 13, which clamp the plates against the spacers 12.

The main driving shaft 14, is supported between the two plates, as best illustrated 45 in Fig. 4, and has loosely mounted upon it a driving gear 15, which is provided with a spring-pressed pawl 16. This pawl engages a ratchet 17, which is secured to the shaft 14. The spring 18, passes through the gear 15, 50 and has one end engaging the tail 20, of the pawl 16, while the opposite end of the spring 21, extends through a perforation in the gear. By this arrangement an extremely long pliable spring is made effective between the gear and the pawl.

The plate 11, has radially punched out flanges 22, which as illustrated herein, are three in number, and serve as adjusting points over which one end of a spring 23, 60 may be secured.

This spring 23, passes about a spring drum or bushing 24, which is secured to a spring casing 26. The inner end of the drum or arbor 24, is slotted as at 27, to engage 65 shoulders 28 formed upon an enlargement

of the spindle 14. This effects a permanent clutch between the casing 26, and the spindle 14.

The casing 26, is of cup form and incloses the spring and spring drum. This casing 70 has struck out lugs 29, to which the outer end of the spring 23, is attached. The ends of the spring are of hook form so that, while one end engages one of the lugs 29, and the casing 26, the other end will engage one of 75 the struck up lugs 22, of the plate 11.

It will be seen from this arrangement that various adjustments for tensioning the spring 23, are possible; inasmuch as said spring may be attached to either of the lugs 29, and to either of the lugs 22, and by then turning the spring drum 24, until its slot 27, engages with the shoulders 28, an adjustment of wide range may be secured. The spring 23, is comparatively light and 85 just sufficient to re-wind the pull-cord 35. The friction of the parts is comparatively great so that a considerable tension may be placed on the spring without driving the parts and, in fact, such a tension as will very 90 rapidly re-act to wind the cord 35.

In applying the device for use, the end of the pull-cord 35, may be made fast to some fixed part of the motorcycle, automobile frame, or convenient fixture, and the 95 spring 23, adjusted to give any desired tension to determine the rapidity of re-action for re-winding the cord after the same has been pulled and unwound from the drum.

In the event of over-running of the parts, 100 under the re-winding action of the spring 23, the loose connections of the respective ends of the spring with the flanges 22, and the lugs 29, prevent re-actionary strains which would cause breakage or injury to the 105 spring. It is obvious that, were the ends of the spring permanently secured to the frame-part 11, and casing 26, there would be liability of breakage upon over-running, to say nothing of the difficulties of assembly 110 and lack of adjustability.

With the arrangement as shown and described, one end of the spring may, by partial rotation, be engaged with one of the lugs 29; and upon rotation of the casing 26, 115 the other end of the spring will be engaged with one of the lugs or flanges 22, as illustrated in Figs. 3 and 6. It is also apparent that renewals of the spring may be effected without difficulty by loosening the nut upon 120 the shaft 14, and removing the winding drum and the casing 26, without disturbing any of the adjustments between the cam, diaphragm, and other driving mechanisms.

A lug 30, is struck out of the casing 26, 125 and projects into a perforation 31, formed in a disk 32. The disk 32, with a co-operating disk 33, and intermediate hub 34, serves as a winding drum for a cord 35.

This pull cord 35, is wound upon the 130

winding drum under the influence of the spring 23, which rotates the casing 26, winding drum and the spindle 14, upon the free movement of the ratchet and pawl 17, and 16.

When the cord is pulled and unwound from the drum, it rotates the spindle 14, and through the ratchet and pawl 17 and 16, drives the gear 15.

10 The gear 15, meshes with a pinion 36, upon the cam spindle 36^a.

This spindle and its pinion 36, have a loose play between fixed bushings 37, 38, which are respectively fixed in the plates 15 10. and 11. The bushing 38, extends through the plate 11, and also passes out through a perforation 39, in the rear end of the casing 4. It serves as a long bearing for the spindle shaft 36^a, which is adjustable therein.

A thrust bearing consisting of an adjusting screw 40, with a check-nut 41, is arranged to determine the end play of the spindle 36^a.

25 The inner end of the spindle 36^a, bears the cam 9, which is preferably secured to an enlarged hub 9^a, which gives stability and weight to the cam in its striking action upon the anvil 6.

30 It is to be understood that the casing 26, passes out through a perforation in the rear of the cylindrical casing 4, so that any adjustment of the mechanism toward and away from the diaphragm 5, is made possible.

The front plate 10, has rearwardly turned lugs 10^a, having screw threaded openings by which locking screws 10^b, may be utilized to lock the mechanism to the casing 4, in any 40 desired position of adjustment. Slots 4^a, are provided in the casing to which the screws 10^b, extend and along which adjustment may be effected. This provides a means for bodily adjusting the mechanism 45 with reference to the diaphragm and the anvil 6.

In order to secure finer adjustments so that the exact and proper striking force may be delivered by the cam 9, to the anvil 50 6, the adjusting screw 40, is employed. It will be seen from the above described arrangement of parts, that with the cord 35, wound upon the drum, a quick pull upon the cord will instantly transmit very rapid 55 rotation to the cam 9. The instant the pull upon the cord is released, the spring 23, winds the cord back upon the drum, allowing the gear 15, pinion 36, and cam 9, with appurtenant parts, to continue their rotation in the same direction in which they were propelled by the pull upon the cord.

60 It will be apparent from the above that by manipulating the cord, any desired degree of force may be applied for driving 65 the gears and the cam 9, and it will be

equally apparent that an initial force of considerable intensity can be applied, or by rapidly pulling upon and releasing the cord, the mechanism may be maintained at a state of high speed.

In fact, the manipulation of the device is entirely under the control of the operator, and therefore any desired intensity of signal tone may be produced.

It is apparent that the exact details of the mechanism herein above described may be varied to a considerable extent without departing from the spirit or intent of the invention which contemplates a unique arrangement of adjustments by which a variety of effects are possible with a simple actuating mechanism.

What I claim as my invention and desire to secure by Letters Patent is:

1. In a signal horn embodying a vibratory diaphragm and a cam for actuating the same, a main driving shaft and gears for driving said cam, a clutch device between the main driving shaft and gears, a winding drum upon said shaft, a spring for winding 85 said drum in one direction and means for automatically and adjustably connecting said spring at its opposite ends to one of a plurality of attaching points.

2. In a signal horn embodying a vibratory diaphragm and a cam for actuating the diaphragm, gears for driving said cam, a frame supporting said gears and cam, a main shaft, a clutch intermediate said shaft and the gears, a spring drum mounted upon 100 the shaft and positively clutched thereto, a casing secured to the spring drum and forming a closure therefor, a spring, a series of adjusting lugs upon the frame, a series of adjusting lugs upon the casing, said lugs 105 providing means for the automatic engagement of the opposite ends of the spring as it is tensioned, and a winding drum adapted to be connected with the casing.

3. In a signal horn embodying a vibratory diaphragm, a supporting frame, gears, and an actuating cam for said diaphragm, a casing inclosing said frame and within which said frame is adjustable, means for adjusting said frame within the casing, a 110 spring barrel casing extending beyond the inclosing casing and having means for attachment to the main shaft, a main shaft extending through said barrel and casing, a winding drum supported thereon, and a 115 winding spring for rotating the main shaft in one direction.

4. In a signal horn embodying a vibratory diaphragm and a cam for actuating the same, a main driving shaft and gears for 125 driving said cam, a clutch device between the main driving shaft and gears for driving said gears and cam in one direction, a casing inclosing said mechanism and provided with a perforation through which the 130

main driving shaft extends, a winding drum upon said shaft, a spring for winding said drum in one direction, means for automatically engaging the ends of said spring 5 for adjustably determining its action with reference to the shaft, and a casing inclosing said spring drum, said casing projecting through the perforation of the main casing and forming a closure therefor.

10 5. In a device of the character described, a main casing, a supporting frame adjustable therein, said frame bearing gears, an extended main shaft, a cam shaft, and an actuating cam for a diaphragm, a diaphragm in the casing, a bearing for the cam shaft extending from the frame and projecting through the casing, adjusting means for the cam shaft arranged in said bearing, a spring barrel casing extending through the 15 main casing and having means for attachment to the main shaft, said shaft extending through the barrel and casing, a winding drum supported thereon, and a winding spring for rotating the main shaft and drum 20

in one direction, said spring being removably attached to the spring barrel casing and the main casing to permit adjustment of said casing with reference to the main shaft.

6. In a device of the character described, a vibratory diaphragm, a driving mechanism, and a cam for actuating the diaphragm, a main shaft for the driving mechanism projecting through a supporting frame, a supporting frame for said parts, a plurality of spring engaging lugs upon the frame arranged about said shaft, a spring barrel removably clutched to said shaft and having a plurality of lugs for automatically engaging one end of a winding spring, a winding spring loosely engaging one of the lugs of the frame and one of the lugs of the spring barrel casing, and a winding drum operatively connected with the main shaft and the spring drum casing. 25 30 35 40
